UNITED STATES PATENT OFFICE

135,974

DESIGN FOR A SUCTION CLEANER CASING OR THE LIKE

Ralph E. Kruck, Springfield, Mass., assignor to
Westinghouse Electric & Manufacturing Com-
pany, a corporation of Pennsylvania

Application August 11, 1942, Serial No. 107,881

Term of patent 14 years

To all whom it may concern:

Be it known that I, Ralph E. Kruck, a citizen
of the United States, residing at Springfield, in
the county of Hampden and State of Massa-
chusetts, have invented a new, original, and
ornamental Design for a Suction Cleaner Casing
or the like, of which the following is a specifica-
tion, reference being had to the accompanying
drawings, forming a part thereof.

Fig. 1 is a perspective view showing a side of
a suction cleaner casing embodying my new
design;

Fig. 2 is a perspective view showing the rear
of the cleaner casing;

Fig. 3 is a perspective view taken from above

and to the rear, showing the top of the cleaner
casing;

Fig. 4 is a perspective view showing the front
of the cleaner casing; and

Fig. 5 is a perspective view taken from the
left-rear, showing the left-side, top and rear of
the cleaner casing.

The dominant feature of the design is shown
in solid lines on the drawings.

I claim:

The ornamental design for a suction cleaner
casing or the like, substantially as shown and
described.

RALPH E. KRUCK.
